UNITED STATES PATENT OFFICE.

GEORGE A. DRIGGS, OF WATERBURY, CONNECTICUT.

DESIGN FOR A PIN-PACKAGE.

SPECIFICATION forming part of Design No. 21,287, dated January 12, 1892.

Application filed October 29, 1891. Serial No. 410,280. Term of patent 14 years.

To all whom it may concern:

Be it known that I, GEORGE A. DRIGGS, a citizen of the United States, residing at Waterbury, in the county of New Haven and State of Connecticut, have invented and produced a certain new and useful Improvement in Designs for Pin-Packages, of which the following is a specification, reference being had to the accompanying drawing, forming a part thereof, and which shows a pin-package conformed and ornamented in accordance with my design.

The leading features of my design comprise the round base having the ornamental bands formed upon its surface and the annular cushion-like band superposed upon the top of the base.

The base has a round-edged outwardly-projecting bead 1, with a smaller bead connected thereto at its upper edge, and immediately above this is a channel or groove 2. Above the groove 2 the base bears an outwardly-projecting band 3, having the parallel grooves or lines 4 upon its surface. The face of this band is in about the same vertical plane with the outer edge of the smaller of the beads at

the bottom of the base, but inside the vertical plane in which lies the outer face of the larger bead 1. Above the band 3 is a diminished neck 5, and this is crowned by a round-edged annular cushion-like ornamental band, whose outer edge lies in about the vertical plane of the neck 5, just referred to, or a little within it.

As will be noticed by an inspection of the drawing, the bead 1 constitutes the greatest diameter of the package. The band 3 is diminished relative to said bead, and the band 6 is still further diminished, and this in a measure contributes to the distinctive appearance of the package. The band 6 is made to contrast in color with the base.

I claim—

The design for pin-packages, substantially as shown and described. 45

In testimony whereof I affix my signature in presence of two witnesses.

GEORGE A. DRIGGS.
